UNITED STATES PATENT OFFICE.

FRANK S. McCauley AND CHARLES W. DIFFENDERFER, OF CHAMBERSBURG, PENNSYLVANIA.

STOP MECHANISM FOR LOOPER MACHINES.

Application filed December 5, 1924. Serial No. 754,137.

To all whom it may concern:

Be it known that we, FRANK S. McCauley and CHARLES W. DIFFENDERFER, both citizens of the United States, and residents of 5 Chambersburg, Franklin County, Pennsylvania, United States of America, have invented certain new and useful Improvements in Stop Mechanism for Looper Machines; and we do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

Our invention relates to stop mechanism 20 for looper knitting machines by which, when a knot occurs in either the needle thread or hook thread or both, is caused a stopping of the machine before the knot in either or both threads reaches the needle or the hook, thus preventing a breaking of these 25 parts of the machine, or a destruction or deterioration of the work.

The needle thread passing through the needle take-up is preferably positively severed when a knot occurs in this thread. A knot in the hook thread positively operates 30 a thread fork to cause the machine to stop independently of the actuation by the take-up, but it operates the same intermediate mechanism.

In our construction we preferably utilize 35 the rebound movement of the spring wire needle take-up, upon a severance of the thread passing through the take-up to the needle, to operate or release the clutch actuating means. Preferably this thread is positively severed by a knife when the thread 40 draws the take-up down.

Details of the invention will hereinafter be more specifically described and claimed.

Referring to the drawings, in which like 45 parts are similarly designated—

Figure 1 is a side elevation of so much of a looper machine, with our invention attached, as is necessary to an understanding of our invention.

Fig. 2 is a plan view thereof.

Fig. 3 is a front view of a portion thereof.

The looper machine is a well known, two thread, construction, and comprises briefly

the following parts: the frame member 1, the point crown 2, needle actuating parts 55 and needle carrier 3 pivoted at 4, its actuating link 5 operated from crank 6, on the driving shaft 7, Figs. 2 and 3, that is driven by a pulley 8 provided with a clutch 9. The clutch is operated by lever 10 and rod 60 11 from the front of the machine by a handle within ready reach of the operator. The clutch 9 shown in engaged position has a shifting muff 22 engaged by a pin 23 on the lever 10. The muff 22 is moved toward the 65 right, Fig. 3, for releasing. A hand crank 12 is provided to actuate the operating shaft to move the sewing mechanism manually when threading the machine or for other purposes. A tension pin 13 is mounted on a standard or bracket 14 which also carries the spring tension discs 15.

There is also provided a wire hook thread take-up 16 and hook thread tensions 17 and 18. Also a wire needle thread take-up 19 75 and tensions 20 and 21. The sewing needle and hook are not shown. The needle thread is indicated by double arrows and the hook thread by single arrows.

With the above explanations, we will proceed to describe our invention.

On the needle carrier 3 we place between the tensions 20 and 21 a knife 50. On the tension pin 13 we secure one end of an arm 51 by means of a screw 52, so that the arm 85 51 may be rotatably as well as axially adjusted on the pin, 13.

In the opposite end of this arm at 53 we pivot a lever 54 having a thread fork 55 at the rear of its pivot. The slot in the fork 90 is wide enough to pass a thread, but not wide enough to pass a knot in the thread. At the opposite side of the pivot 53 this lever is bent so that its tail 56 normally lies below a horizontal rod 57 of a trigger lever 58. 95 This trigger lever has a short trigger hook 59 extending but a short distance beyond its pivot screw 60 in the frame of the machine, or, as shown, in a removable auxiliary casting or auxiliary frame member 61 detachably secured to the main frame 1 of the machine. Below this trigger arm in the casting 61 is a stop-pin 62 for the trigger arm 58.

The trigger hook 59 engages a similar hook 63 on the long arm of a release lever

64 pivoted on a screw 65 in the auxiliary frame member 61. The tail 66 of the lever 64, here shown as having a hooked shape, acts as an abutment for a spring-urged rod 67.

The release lever 64 is urged away from the trigger hook 59 by a leaf spring 68, and a yoke-shaped stop 69 on the auxiliary frame 10 61 prevents this lever, when released, from turning too far on its pivot 65.

The horizontal rod 57 of the trigger lever lies above and in the path of the needle thread take-up 19.

We also provide a stationary fork 70 for 15 the needle thread, similar to fork 55 and for a similar purpose, namely, to arrest the thread at a knot therein. This stationary fork is conveniently secured at the bracket 14, or other stationary part.

The auxiliary frame member 61 has a portion 61^a at right angles thereto in which the rod 67 is mounted to slide, and has an elongated recess or aperture 71 through which the actuating coil spring 72 surrounding 20 this rod and its pin 73 and abutment washer 74 may be inserted when assembling the parts. The spring 72 urges the rod 67 toward the hooked abutment tail 66 of the lever 64 when the trigger is set, and when 25 the trigger is released the tail moves past the end of the rod and allows this end to be projected beyond the lever.

The auxiliary frame member has at the end of the portion 61^a an L-shaped portion 30 61^b in which is mounted a two-armed lever 75 whose upper end is pivoted to the end of the rod 67 at 76. This pivotal connection may be a loose one, or the rod 67 may have bearing in the auxiliary frame portion 61^a 35 sufficiently loose to readily permit the oscillation of this lever. The nose 77 of this lever engages a shifting pin 78 engaging the same groove 22 in the movable element 9 of the clutch, that the shifting pin 23 engages 40 of the hand-operated stop lever 10.

This auxiliary shifting pin 78 is mounted in one arm of the bell-crank lever 79 pivoted at 80 in a bracket 81 secured on the machine frame. The other arm of this bell-crank 50 lever is connected by a rod 82 adjustable as to length to a pedal 83, so that the operator shall have both the usual hand-operated stop lever of the machine and the foot-operated stop lever 79, so that she can stop the 55 machine with her foot when her hands are busy placing the stockings on the supporting points of crown 2.

The operation is as follows:

Should a knot occur in the needle thread 60 it will be stopped by the needle thread fork 70 and not feed past this point. The thread, however, beyond this point is continued to be used, and the wire needle thread take-up 19 will be drawn down until that portion of 65 the thread between the tension eye 20 and

the eye of the take-up 19 strikes the knife 50 and is severed. The take-up being thus released springs back and strikes the rod 57 of the trigger lever 58, releases the trigger hook 59 from engagement with the stop-lever retaining hook 63 and permits this lever to be thrown up by its spring 68, so that its abutment tail 66 moves past the end of rod 67 retained thereby, and permits the 70 rod 67 to be suddenly shot past this lever. 75

This movement of the rod is stopped by its pin 73 striking against an end wall of the recess 71. The rod 67 draws the upper end 80 of lever 75 with it. The urge of this lever then moves the shift pin 78 to release the clutch and stop the operation of the machine.

Should a knot occur in the hook thread, this knot will engage the fork 55 on lever 85 54 and cause the tail 56 of this lever to strike the horizontal rod 57 of the trigger lever 58 and thus operate this lever to stop the machine, as above described.

The pedal 83 is an additional means for 90 stopping the machine by the operator for actuating the auxiliary shift pin 78. This pedal when operated will also cause the clutch to engage to start the machine, and at the same time retract the rod 67 so that 95 the trigger can be reset, or it may be reset by hand.

These arrangements may be readily attached to existing machines and do not require reconstruction of the machine.

They not only effect a saving in thread, 100 but also a great saving in semi-finished work as well as time, in which the machine would otherwise be idle to remove spoiled work, and repair broken parts.

We claim—

1. The combination with a looper machine having a clutch to place the machine in and out of operation and a take-up; of a knot holding element, a clutch operating means including a trigger mechanism arranged to 110 be actuated by said take-up when the thread passing through said take-up is severed, and a knife to positively sever thread when said take-up is drawn down by reason of a knot 115 in the thread.

2. The combination with a looper machine having a clutch to place the machine in and out of operation and a take-up; of means to hold or retain a knot in the thread passing to the take-up, clutch operating mechanism 120 means to sever the thread when it is held and the tension on the take-up increases and means operated by said take-up when the thread is severed to actuate the clutch mechanism to stop the machine.

3. The combination with a looper machine having a clutch to place the machine in and out of operation and a take-up; of clutch operating mechanism including a trigger 125 means arranged to be released by said take-

up, a stationary thread fork to hold or retain a knot in the thread passing through said take-up, whereby when the thread is severed the take-up will operate said trigger means to throw the clutch out.

4. The combination with a looper machine having a clutch to place the machine in and out of operation and a take-up; of a clutch engaging and operating member, a pivoted lever to operate said member, a spring actuated rod connected to said lever, a retaining lever against which said rod rests, and a trigger to hold the latter lever and arranged for operation by the take-up.

5. The combination with a looper machine having a clutch to place the machine in and out of operation and a take-up; of a clutch shifting member, a pivoted lever to operate said member, a rod connected to said lever, a spring to actuate said rod, trigger mechanism cooperating with said rod, comprising a rod-holding lever, a trigger for said lever arranged to be actuated by said take-up to permit the lever to release said rod to cause the clutch to be thrown out, and means acting on said member to return said pivoted lever and rod against the action of said spring preparatory to resetting the trigger, and to simultaneously throw the clutch into engagement.

6. The combination with a looper machine having a clutch to place the machine in and out of operation and a take-up; of a clutch operating member, a pivoted lever to operate said member, a rod connected to said lever, a spring to slide said rod, a pivoted stop lever having a short arm against which said rod abuts and a long arm provided with a hook a knot holder, a trigger having a hook on one end engaging the first-mentioned hook and its opposite end arranged to be operated by the take-up when the thread is severed.

7. The combination with a looper machine having a clutch to place the machine in and out of operation and a take-up; of means to sever the thread leading through the take-up when the tension increases abnormally a trigger-controlled clutch shifting means arranged for actuation by said take-up when its thread is severed to release the clutch, and pedal-actuated means to cause the re-engagement of the clutch and permit the re-setting of the trigger-controlled means.

8. The combination with a looper machine having a clutch to place the machine in and out of operation and a spring take-up; of a thread fork to retain a knot in the take-up thread and cause the take-up to be pulled down, a knife in the path of said thread when the take-up is pulled down, a trigger operated by the take-up on its rebound when the thread is severed and having a trigger hook, a spring-urged stop lever having a hook engaged by the trigger hook, a spring-

urged rod normally stopped by said stop lever, a pivoted lever connected to said rod, a clutch shifting device actuated by the latter lever, and pedal-operated means to reset said rod and simultaneously re-engage the clutch and permit the setting of the trigger.

9. The combination with a looper machine having a clutch to place the machine in and out of operation and a take-up; of a trigger-controlled means to release said clutch and arranged to be actuated by said take-up when released by one of the sewing threads, and a movable knot-engaging means for the other sewing thread also arranged to operate said trigger means when a knot prevents the passage of said other thread past said means.

10. The combination with a looper machine having a clutch to place the machine in and out of operation and a spring take-up; of a knot holding fork, a trigger-controlled means to release said clutch, arranged to be operated by said take-up, a knife to sever the take-up thread when the take-up is drawn down, said trigger-controlled means operated by the rebound of said take-up, a pivoted hook thread fork also arranged to operate said trigger means, and a pedal operated means to re-engage the clutch and simultaneously permit the re-setting of said trigger-controlled means.

11. The combination with a looper machine having a clutch to place the machine in and out of operation and a spring take-up; of a stationary thread fork to hold or retain the take-up thread, a stationary knife to sever the take-up thread when the take-up is pulled down, and a trigger-controlled clutch-operating means arranged to be operated by rebound of the spring take-up when the thread is severed.

12. The combination with a looper machine using a hook thread and a needle thread and having a clutch and a needle thread take-up; of means automatically released by said take-up when the tension on needle thread is suddenly released, to automatically release said clutch, and means operated by a knot in the hook thread to also actuate said mechanism to automatically release said clutch.

13. The combination with a looper machine having a clutch to place the machine in and out of operation and a spring take-up; of means to hold or retain a knot in the thread passing to the take-up, a knife onto which the thread passing the take-up is moved when retained by a knot, and means operated by the take-up when it rebounds upon a sudden release of the tension on the thread to actuate said clutch.

14. In a looper machine having a pivoted, swinging needle arm, a spring take-up thereon and a clutch mechanism for starting and stopping the machine; a knot-holding fork,

and a trigger mechanism for releasing the clutch arranged to be actuated by the take-up when its thread is severed.

15. In a looper machine having a pivoted, swinging needle arm; a spring take-up thereon and a clutch mechanism for starting and stopping the machine; a stationary knot-holding fork, and a trigger mechanism arranged to be operated by the take-up when

its thread is parted, and a pivoted looper ¹⁰ thread knot-holding lever also arranged to operate said trigger mechanism when actuated by a knot in the looper thread.

In testimony that we claim the foregoing as our invention, we have signed our names.

FRANK S. McCUALEY.
CHARLES W. DIFFENDERFER.
